FOLDING SLIDING DOOR

Filed Jan. 23, 1923

2 Sheets-Sheet 2

UNITED STATES PATENT OFFICE.

PHILIP LANG, OF CEDAR FALLS, IOWA, ASSIGNOR TO WAGNER MANUFACTURING COMPANY, OF CEDAR FALLS, IOWA, A CORPORATION OF IOWA.

FOLDING SLIDING DOOR.

Application filed January 23, 1923. Serial No. 614,465.

To all whom it may concern:

Be it known that I, PHILIP LANG, a citizen of the United States, residing at Cedar Falls, in the county of Blackhawk and State 5 of Iowa, have invented certain new and useful Improvements in Folding Sliding Doors, of which the following is a specification:

My invention relates to improvements in folding sliding doors.

10 The object of my invention is to provide a folding sliding door arrangement whereby all of the door sections are supported by hangers traveling on a single track and so arranged that all of the door sections are 15 caused to be folded and travel around against the inner face of the front wall of the building and all of the door sections folded flat against each other so that they will take up very little room and will not form any obstruction in the door way.

Another object of my invention is to provide a folding sliding door arrangement of this character which is simple in construction, having very few parts and at the same 25 time obtaining the necessary strength to prevent the sagging of the door section and having certain details of structure and combination of parts hereinafter more fully set forth.

30 In the accompanying drawings—

Figure 1 is a front view of a building showing my folding sliding door arrangement and looking from the inside of the building.

35 Figure 2 is a top plan view partly broken away showing in full lines the door sections in their inwardly folded open position.

Figure 3 is an enlarged vertical section taken through one of the door sections when 40 closed and showing the hanger as applied.

Figure 4 is an enlarged side elevation showing the hanger and showing the track in section.

Referring now to the drawing 1 represents the front wall of a building and 2 the door opening, which as shown is of considerable width, requiring five door sections to close the same. On the inside of the front wall of the building above the door way or 45 opening is arranged the horizontal track 3, which has the end 4 extending beyond the door opening and the opposite end terminating a short distance from the opposite end of the door opening, as indicated at 5. This

track is supported by the wall of the building by any desired number of brackets 6 arranged at different points along the same. The construction of the track 3 is preferably of the tubular form as shown in Figure 3 of the drawings which absolutely prevents 60 the hangers from jumping off the track, but it will be understood that any desired form of track could be used without departing from my broad invention.

The door sections, five in number are 65 designated by the reference numerals 7, 8, 9, 10 and 11 all of the same width and constructed exactly alike and hinged together as will be hereinafter more fully described. The door section 7 is hinged to the frame 12 70 of the door opening by the strap hinges 13 which are preferably three in number although the number and character of these hinges could be varied without affecting the invention. These hinges as shown in Figures 1 and 2 of the drawings are on the inside so that the door section 7 can swing around against the inner face of the front wall of the building. Hinged to the opposite edge of the door section 7 by the hinges 14 is the door section 8 so as to swing in the opposite direction to the door section 7 against the outer face thereon, and hinged to the opposite side of the door section 8 by the hinges 15 on the inside is the door 85 section 9. The door section 9 has hinged to the other edge by the outside hinges 16 the door section 10 and the opposite edge of the door section 10 has hinged thereto by the inside hinges 17 the door section 11, which 90 section has its opposite edge free and whereby the said section is free to open and close on the hinges 17 as a single door in the event a person desires to enter the building.

The door section 8 has secured to its upper edge the hanger 18 which travels within the tubular track 3 as clearly shown in Figure 3 of the drawings. The door section 10 has secured to the inner face at the upper edge a second hanger 19 which is constructed exactly like the hanger 18 except that the connecting arm of the two pivots is longer as will be described later. The door section 9 intermediate the door sections 8 and 10 supported by the hangers has a roller 20 which 100 rolls on the floor of the building and forms an additional support for the door sections to prevent them from sagging and touching

the floor. The door sections 8, 9 and 10 are provided at their upper ends with bolts 21, 22 and 23 which brace the door when closed and will, relieve the door sections of any undue strain brought on the same. The door sections 8 and 10 may also have bolts 24 and 25 at their lower ends to further relieve the door sections of any undue strains, either from the inside or outside. The section 11 5 may have a pivoted latch or any desired fastening means 26 for locking the said section against inward movement. This fastening means is adapted to be operated from the inside or outside of the building as is readily 10 understood.

The door hangers 18 and 19 are of the form shown in Figures 3 and 4 of the drawings, and each consists of the plate 27 having openings by means of which it is either 15 screwed or bolted to the door section and carrying at its upper end the pivot 28 upon which is mounted the arm 29, and carried by the outer end of the arm is a bearing 30 rotatably mounted upon the stud 31. 20 This stud is supported by a carriage 32 rolling within the tubular track 3 whereby the door sections not only move longitudinally on the track but are allowed to fold on their 25 hinges with respect to each other. The 30 hinges between the door sections being arranged as heretofore described, allows every other door section to fold in the opposite direction as fully shown in Figure 2 of the drawings. As heretofore described the two 35 hangers 18 and 19 are constructed exactly alike with one exception and that is the arm 33 of the hanger 19 is longer than the arm 34 of the hanger 18 whereby provision 40 is made for the thicknesses of the several sections of the door. This long arm 33 of the hanger 19 allows the section 10 to swing in a sufficient distance to lie flat against the door section 9.

In operation the door sections operate as a 45 single door that is, it is only necessary to push on the door section 11 and the several sections break joint at their hinged edges and at the same time the whole door moves longitudinally on the track, and the door 50 sections one by one will fold over against each other parallel to the inner wall of the building, where they are completely out of the way and take up very little room.

Having thus described my invention, 55 what I claim and desire to secure by Letters Patent is—

1. In a door construction, the combination 60 with a track, of a series of door sections hinged together, one end section hinged to a permanent support, a hanger connected to one of the intermediate door sections and traveling on the track, and a second hanger connected to one of the other door sections and traveling on the track and constructed 65 to allow all of the door sections to fold

around against each other beyond the permanent support at one side of the door opening.

2. In a door construction, the combination 70 with a track, of a series of door sections hinged together, one end section hinged to a permanent support, a hanger connected to one of the intermediate door sections and traveling on the track, and a second hanger connected to one of the other 75 door sections and traveling on the track and constructed to allow all of the door sections to fold around against each other beyond the permanent support, at one side of the door opening and a roller carried by one of the intermediate sections and rolling on the floor. 80

3. In a door construction, the combination 85 with a track, of a series of door sections hinged together, one end section hinged to a permanent support, a hanger pivotally connected to one of the intermediate door sections and traveling on the track, and a second hanger pivotally connected to one 90 of the other door sections and traveling on the track and constructed to allow all of the door sections to fold around against each other beyond the permanent support. 95

4. In a door construction, the combination 100 with a track, of a series of door sections hinged together, one end section hinged to a permanent support, a hanger traveling on the track and having a pivoted arm pivotally connected to one of the intermediate door sections, a second hanger traveling on the track and having a pivoted arm longer than the pivoted arm of the first hanger and 105 pivotally connected to one of the door sections beyond the first hanger, whereby all of the door sections can fold around on each other beyond the permanent support. 110

5. In a door construction, the combination 115 with a track, of a series of door sections hinged together, one end section hinged to a permanent support, a hanger traveling on the track and having a pivoted arm pivotally connected to one of the intermediate door sections, a second hanger traveling on the track and having a pivoted arm longer than the pivoted arm of the first hanger and 120 pivotally connected to the door section next to the last from the permanent support, whereby all of the door sections can fold around on each other beyond the permanent support. 125

6. In a door construction, the combination 130 with a single track, of a series of door sections hinged together, one end section hinged to a permanent support, two hangers traveling on the track and having lateral pivoted arms of different length pivoted to different intermediate door sections, whereby all of the door sections can fold around on each other beyond the permanent support. 135

7. In a door construction, the combination with a single track, of a series of door sections hinged together, one end section hinged to a permanent support, two hangers 5 traveling on said track and connected to different door sections and constructed to allow all of the door sections to fold around on each other beyond the permanent support.
- 10 8. In a door construction, the combination with a single track, of a series of door sections hinged together, one end section hinged to a permanent support, two hangers traveling on said track and having arms of 15 different lengths connected to different door sections, whereby all of the door sections can fold around on each other beyond the permanent support.
9. In a door construction, the combination with tracks having a series of supports 20 along its length, of a series of door sections hinged together, one end section hinged to a permanent support, a hanger traveling on the track and having a pivoted arm connected to one of the intermediate door sections, a second hanger traveling on the track between two of the different supports and having a pivoted arm longer than the pivoted arm of the first hanger and pivotally connected to one of the other door sections beyond the first hanger, whereby all of the door sections can fold around on each other 25 beyond the permanent support.
- 30

In testimony whereof I affix my signature.

PHILIP LANG.
